UNITED STATES PATENT OFFICE.

LÉON GRIVEAUD, OF PARIS, FRANCE.

POST FOR SUPPORTING TELEGRAPH-WIRES, &c.

SPECIFICATION forming part of Letters Patent No. 761,294, dated May 31, 1904.

Application filed July 28, 1902. Serial No. 117,325. (No model.)

To all whom it may concern:

Be it known that I, LÉON GRIVEAUD, a citizen of the French Republic, and a resident of Paris, France, have invented certain new and useful Improvements in Posts for Supporting Telegraph-Wires, Cables, and the Like, of which the following is a specification.

This invention relates to metal line-posts and station-posts which can be employed with advantage as supports for wires or cables used in telegraphy, telephony, transmissions of power, and tramways on the trolley system, as well as for all kinds of lighting and signaling apparatus.

The principle consists in forming a hollow prismatic section by means of laminated or embossed configurations placed side by side, with or without intervals, and connected simply from point to point by means of rivets, bolts, &c. The support may be divided into truncal sections of different shapes proportioned to the strain to be resisted, fitting into one another like the telescoped tubular posts. The station-posts may be constructed in a similar manner to the line-posts, the conditions to be fulfilled being much alike in both cases and the former only differing generally from the latter as regards the way in which they are fixed, the line-posts being insulated and fixed with the lower part in the ground, while the station-posts are fixed by horizontal rods or brackets to constructions already existing—a wall, a roof, or a post.

The external form of my post or of the truncal divisions of which it consists has induced me to give it the distinctive name of "prism-post." The metal employed in making it may be of any kind. The configurations forming the sides of the hollow prism are made of iron or steel or any other hard substance produced by metal-works. The fixing blocks or frames employed for insuring the fixture of the posts are made of cast-iron, iron, or wood, &c.

In order to complete the explanation, I have indicated in the drawings accompanying this application for a patent some arrangements in conformity with the principle enunciated and which may be more generally in use.

Figure 1 is a view in elevation giving a general representation of a prism-post composed of three truncal divisions A A' A''. It is furnished with a base S, annular moldings D, and an apex P, which may be made of cast-iron and of any shape. Advantage is taken of the base S to disguise a strengthening part running nearly to the upper part of the base in the dangerous part of the post. This part consists of a double T-piece E, arranged as shown in the horizontal sections illustrated in Figs. 5 and 10. The lower end of this piece E may be provided with two angle-irons riveted or bolted to the part which most directly bears the weight of the post.

Figs. 2 and 3 illustrate the former a piece in elevation and the latter a horizontal section of a very simple and very useful contrivance. The pieces A, which form the sides of a hollow prism, are of U-shape section, forming a square or rectangular plane. These pieces A are firmly fixed at different points by cast-iron frames C and bolts B.

Figs. 4 and 5 represent a post in the interior of which a double T-piece E is arranged over the whole height of the support, which increases its strength and at the same time closes the space left between the inturned ends of piece A. The interior frames C are double. They may, however, be entirely omitted if the feet of the T-piece E be furnished with a projection against which the flanges of the pieces A can rest. This continuous projection could be replaced by "screw-pegs" placed at certain distances apart.

Fig. 6 is a horizontal section in which the pieces A hold tightly between their flanges doubly-grooved pieces E'. The pieces E' may be continuous or simple short pegs. In this figure the metal frames are replaced by blocks of wood.

Figs. 7 and 8 represent a post in which the pieces A are semicircular hollow pieces rolled, bent, or embossed. If there be any space between these pieces, it may be stopped throughout or over a part of the height of the support by a configuration of any kind, such as E'', which will at the same time increase the strength and fill up the space. The pieces A

may be screwed onto the frame C or be tightened by means of a hoop F in one piece put on hot or in two pieces bolted together.

5 Figs. 9 and 10 represent a piece in elevation and a section of a post in which the parts A directly "lock" a double T-piece E. The parts may be kept together by the bolts B without the employment of frames or interior pieces.

10 In Fig. 11 the double T-piece which forms a part of the preceding construction is replaced by two single T-pieces E', held tightly by the arms or flanges of the pieces A and simply connected at certain points by bars H, fixed to the bodies of the T-pieces.

15 *General arrangement.* — The description given above and the drawings which accompany this application can only serve for more clearly fixing the principle explained. It will 20 be seen that a transverse section may be a polygon of any kind, even a circumference, and consists of elements of different forms rolled, bent, or embossed. I thus reserve not only the right of making use of configurations 25 known in commerce, but likewise that of rolling special configurations which may appear to me to be more suitable, either owing to their particular form or their more economical transverse dimensions. I can, 30 for example, have rolled U-shaped forms of slight thickness or with very wide flanges in order to place them together without any intervals, the edges of the arms being planed or not planed. With the purpose of filling 35 up the spaces between the angular pieces or of increasing the strength of the support I can employ metal or wooden rods or other

configurations or again fill up entirely the whole hollow interior of a truncal division with some inert or resistant material, such as cement 40 or mortar. The interior frames, when these are necessary, may be made of wood, cast-iron, iron, &c. In order to keep the angular pieces at proper distances apart, cast-iron bars or pieces of iron rolled in double T shape, in U 45 shape, sheet-iron bent or embossed, tube ends, &c., may be used if the internal hollow space is in the form of a regular polygon. The joints of the different truncal divisions may likewise be varied according to circumstances and differ from the arrangements described, and shown in the drawings.

It will be understood that a fixed joint may be effected by simply riveting together the parts of the truncal divisions which lap one 50 over the other to the extent necessary.

Having now fully described my invention, what I claim, and desire to secure by Letters Patent, is—

A post of the character described comprising a plurality of sections telescoping within each other, each of the sections comprising separable members spaced apart, means for spacing said members, said means closing the space between the members, means for securing the members and said spacing means simultaneously together.

In testimony whereof I have hereunto set my hand in presence of two witnesses.

LÉON GRIVEAUD.
